UNITED STATES PATENT OFFICE.

ALFRED B. ROSEBOOM, OF CHICAGO, ILLINOIS.

TOBACCO MOISTENER.

Application filed May 13, 1922. Serial No. 560,523.

To all whom it may concern:

Be it known that I, ALFRED B. ROSEBOOM, residing at Chicago, in the county of Cook, State of Illinois, have invented a certain new and useful Tobacco Moistener, of which the following is a specification.

It is an object of my invention to provide a moistener for tobacco pouches, or any other container, which is durable, efficient and inexpensive in construction.

It is a further object to provide a device of this class, of small compact structure, so arranged as to work its way through the tobacco in the pouch and at the same time not interfere with pouring the tobacco from such pouch.

It is a further object to provide a device of this class so arranged as to maintain the plunger plate in position under a yielding or resilient pressure.

The above and other features of novelty, advantages and capabilities will become apparent from a detailed description of the accompanying drawings in which I have illustrated a tobacco moistener embodying one form of my invention, but the construction there shown will be understood as illustrative and not as defining the limits of my invention.

Fig. 1 is a sectional view of a tobacco pouch showing a tobacco moistener, embodying one form of my invention.

Fig. 2 is a perspective view of a tobacco moistener embodying one form of my invention, and

Fig. 3 is a sectional view of the same.

Referring to the drawings in detail, the moistener consists of a semi-spherical metal casing 10, provided with a plurality of openings 11; the casing contains compressed absorbent material 12, in the instance shown, sponge material. After inserting the absorbent material within the casing a plunger

plate 13 is placed on top thereof, and pressed downwardly sufficiently to put the absorbent material under compression. The resilient upper edge of the casing is bent inwardly and downwardly as shown at 14, until a portion thereof engages the plunger plate 13, so that it is held by the edges 14 under a resilient or yielding pressure. In utilizing the device, all that is necessary is to immerse within water and press downwardly on the plunger plate 13, then release the pressure, whereupon water or other moistening fluid, as the case may be, is drawn into the casing 10 and absorbed by the material 12. The moistener is then thrown into the pouch and due to its weight and configuration, it works its way around through the tobacco in the pouch, giving off moisture, thus preserving the tobacco in the proper condition and preventing it from becoming dry.

Having thus described my invention, I claim,

1. In a tobacco moistener, the combination of a small compact casing provided with a plurality of openings, a body of absorbent material within the casing and a plunger plate held in position against said absorbent material by an integral, resilient flange on said casing.

2. In a tobacco moistener, the combination of a small, compact casing, a body of absorbent material within the casing and a plunger plate held within said casing and adapted to press against said absorbent body.

In witness whereof I hereunto subscribe my name to this specification in the presence of two witnesses.

ALFRED B. ROSEBOOM.
